UNITED STATES PATENT OFFICE.

EDGAR M. BOUTON, OF EAST PITTSBURGH, AND RAY P. HIGBEE, OF WILKINSBURG, PENNSYLVANIA, ASSIGNORS TO WESTINGHOUSE ELECTRIC AND MANUFACTURING COMPANY, A CORPORATION OF PENNSYLVANIA.

TWO-SPEED ALTERNATING-CURRENT ELEVATOR CONTROL.

Application filed October 11, 1922. Serial No. 593,665.

To all whom it may concern:

Be it known that we, EDGAR M. BOUTON, a citizen of the United States, and a resident of East Pittsburgh, in the county of Allegheny and State of Pennsylvania, and RAY P. HIGBEE, a citizen of the United States, and a resident of Wilkinsburg, in the county of Allegheny and State of Pennsylvania, have invented a new and useful Improvement in Two-Speed Alternating-Current Elevator Controls, of which the following is a specification.

Our invention relates to motor-control systems and it has particular relation to such systems of control as are employed in connection with elevators, machine tools and similar machines.

The object of our invention is to provide means for controlling the speed and torque of an alternating-current motor of the two-speed type, commonly employed in elevator service and having separate low and high-speed windings.

Our invention is more particularly applicable to the control of a two-speed motor of the well-known squirrel-cage type.

In the operation of alternating-current motors of the type herein described, it is common practice to start the motor by connecting its low-speed winding to the source of power and, thereafter, transfer directly to the high-speed winding, with or without resistor in circuit therewith, and finally exclude the low-speed winding from circuit.

In such systems, some difficulty has been experienced in obtaining smooth acceleration. In our system of control, we propose to start the motor by means of its low-speed winding, next connect the high and low-speed windings in series relation, then shunt the low-speed winding with a resistor of suitable value to weaken the effect of the low-speed winding and finally connect only the high-speed winding in circuit. When both high and low-speed windings are in circuit simultaneously, an intermediate speed is obtained which, in certain instances, is rather close to the minimum speed. With a motor having a three-to-one speed range, the intermediate speed is only about 25 per cent greater than the minimum speed. By weakening the low-speed winding, a second

and higher intermediate speed is obtained from which the transition to full speed is less abrupt.

Our invention will be described in connection with the accompanying drawing, in which

Figure 1 is a diagrammatic representation of a two-speed, three-phase alternating-current squirrel-cage motor employed in connection with our invention,

Fig. 2 is a diagrammatic representation of circuits and apparatus embodying our invention,

Fig. 3 is a diagrammatic representation of the control circuits employed in the operation of the system shown in Fig. 2, and

Figs. 4 and 5 represent, diagrammatically, certain of the main connections employed in our system.

A two-speed alternating-current motor 1 is provided with low-speed primary windings 2 and high-speed primary windings 3. These windings are so arranged that they may be connected externally to resistors. Resistor sections 4 are connected in circuit with the motor windings and may be excluded, when so desired, by electro-magnetic switches 5. Resistor sections 6 may be connected in shunt relation to the winding 2 by means of electromagnetic switches 7. Switches 5, 7 and 8 are provided with suitable dash-pots 9, or other devices for retarding their closing movements.

Switches 8 control circuits for excluding the low-speed motor windings 2, and switches 10 are connected for excluding the high-speed motor windings 3 from circuit. An electro-magnetically operable switch 11 is controlled by means of knife-switches 12.

It is apparent that, in addition to the line switch 11, reversing switches may be employed in the customary manner but these have been omitted since they constitute no part of our invention. We provide a manually operable switch 13, as illustrated in Fig. 3 for transferring the motor from low to high-speed connections. A relay 14, having an operating coil 15, is also controlled by means of the switch 13. An interlock 16 is mechanically connected to switch 7. Switch 10 is provided with a normally open interlock 17 and a normally closed inter-

lock 18. A normally closed interlock 19 is attached to switch 8. Power is supplied from a suitable source, for the operation of our system, through line conductors 20, 21 and 22.

Assuming the apparatus to be in its inoperative or illustrated positions, and also assuming that no power has been supplied to conductors 20, 21 and 22, when power is supplied to the line conductors, switch 10 (Fig. 3) immediately closes, since its operating coil is connected, through interlock 19 and relay 14, to conductors 21 and 22. Switch 5 is thereafter closed when its operating coil is connected to conductors 21 and 22 through interlock 17 of switch 10.

To start the motor, switches 12 are next closed to connect the operating coil of lines switch 11 to conductors 21 and 22 (Fig. 2.). Since switches 5 and 10 are closed, it is evident that the motor is started with low-speed windings 2 only in circuit. The motor is further accelerated by closing switch 13 (Fig. 3) thereby energizing the operating coil 15 of relay 14. The opening of relay 14 effects the opening of switch 10 to insert the high-speed windings 3 in series relation with the low-speed windings 2.

The motor then accelerates to a speed corresponding to the excitation produced by the series connections of its low and high-speed windings. Switch 7 is closed by means of the interlock of the switch 10, which completes a circuit for the operating coil of switch 7, extending through switch 13 to line conductors 20 and 21. The opening of switch 10 affects the opening of switch 5 through the interlock 17, thereby inserting resistor sections 4 in series relation with motor windings 2 and 3. (Fig. 4).

The closure of switches 7 inserts resistors 6 in shunt relation to the windings 2. The magnetization of primary windings 2 is thus reduced in accordance with the effective valves of resistors 4 and 6 to further accelerate the motor. (Fig. 5.) Finally, switches 8 close to exclude the low-speed circuits and to energize only the high-speed windings 3. The motor now operates at its maximum speed.

To effect slow-down, switch 13 is opened, thereby opening switches 7 and 8 and closing switches 10. It will be noted that switches 5 are already open and resistors 4 and low-speed windings 2 are now in circuit, while high-speed windings 3 are short-circuited. The insertion of resistors 4 reduces the magnetization of the low-speed windings 2, so that a cushioning effect results during the slow-down, prior to the operation of the motor at its minimum speed. Switches 5 are finally closed to short-circuit the resistors 4 and further decrease the motor speed.

In Figs. 4 and 5, we have illustrated the

intermediate speed connections in which the motor windings are arranged first in series relation and then, as illustrated in Fig. 5, the low-speed windings 2 are shunted by means of the illustrated resistors. These 70 connections have been found necessary only during the accelerating period. Deceleration is satisfactorily accomplished by the insertion of resistors in series relation with the low-speed windings when the high-speed 75 windings are excluded from circuit. In some instances, it may be desirable to substitute reactors of suitable value in place of the series resistors 4 or in place of the shunt resistors 6. The effect of resistance and 80 reactance in motor circuits is well understood and will require no further explanation. Also, for deceleration particularly, it may be advisable to connect resistors in shunt relation to the high-speed windings instead 85 of entirely excluding the windings prior to operation on the low-speed windings.

We claim as our invention:

1. The method of accelerating an alternating-current motor having low and high- 90 speed windings which consists in connecting the low-speed windings in circuit, connecting the low and high-speed windings in series relation, weakening the effect of said low-speed windings and finally excluding said 95 low-speed windings from circuit.

2. The method of accelerating an induction motor having low and high-speed primary windings which consists in connecting the low-speed windings in circuit, connecting 100 the low and high-speed windings in series relation, weakening the effect of said low-speed windings and finally excluding said low-speed windings from circuit.

3. The combination with an alternating- 105 current motor having a high and a low-speed winding and controlling means therefor, of a plurality of resistors, means for connecting said windings and some of the resistors in series relation and means for connecting others of said resistors in parallel relation to one of said windings.

4. The combination with an alternating-current motor having low and high-speed primary windings and controlling means 115 therefor, of a plurality of resistors, means for connecting said windings and some of the resistors in series relation and means for connecting others of said resistors in parallel relation to said low-speed winding.

5. The combination with an alternating-current motor having a low and a high-speed winding, of means for connecting said windings in series relation and means for weakening the magnetization of one of said 125 windings while so connected.

6. The combination with an alternating-current motor having a low and a high-speed winding connected in series relation, of 130 means for energizing only the low-speed

winding, means for energizing said windings simultaneously and means for gradually shunting said low-speed winding.

7. The combination with an alternating-current motor having low and high-speed primary windings, a plurality of speed-controlling resistors associated therewith, and electro-responsive means for selectively rendering the speed windings effective or

ineffective and for connecting said resistors in shunt relation to certain of said windings during acceleration and deceleration of the motor.

In testimony whereof, we have hereunto subscribed our names this 7th day of October, 1922.

EDGAR M. BOUTON.
RAY P. HIGBEE.
